US00D469821S

(12) **United States Design Patent** (10) Patent No.: **US D469,821 S**
Manville (45) Date of Patent: **** Feb. 4, 2003**

- (54) **CRAFT KIT CONSTRUCTION COMPONENT—SIXTEEN-PETAL FLOWER FORM**
- (75) Inventor: **Richard B. Manville**, Los Angeles, CA (US)
- (73) Assignee: **Mattel, Inc.**, El Segundo, CA (US)
- (**) Term: **14 Years**
- (21) Appl. No.: **29/157,995**
- (22) Filed: **Mar. 26, 2002**
- (51) LOC (7) Cl. **21-01**
- (52) U.S. Cl. **D21/488**
- (58) Field of Search D21/483, 484, D21/488-490, 493-495, 503, 561, 398, 468-476, 478-480; 446/85, 103, 104, 121, 128

Primary Examiner—Raphael Barkai

(74) Attorney, Agent, or Firm—Kolisch Hartwell, P.C.

(57) **CLAIM**

The ornamental design for a design craft kit construction component—sixteen-petal flower form, as shown and described.

DESCRIPTION

FIG. 1 is a perspective view of the invention;
FIG. 2 is a plan view of the invention.

1 Claim, 1 Drawing Sheet
